UNITED STATES PATENT OFFICE.

BERTRAND S. SUMMERS, OF PORT HURON, MICHIGAN, ASSIGNOR TO THE NATIONAL FIBER TEXTILE COMPANY, OF NEENAH, WISCONSIN, A CORPORATION OF WISCONSIN.

PAPER YARN AND PROCESS OF MAKING SAME.

1,271,098.

Specification of Letters Patent. Patented July 2, 1918.

Application filed February 6, 1917. Serial No. 146,998.

To all whom it may concern:

Be it known that I, BERTRAND S. SUMMERS, a citizen of the United States, residing at Port Huron, in the county of St. 5 Clair and State of Michigan, have invented certain new and useful Improvements in Paper Yarns and Processes of Making Same, of which the following is a specification.

10 My invention relates to improvements in paper yarn and process of making same, and has particular reference to a paper yarn used in the manufacture of rugs or carpets.

Prior to my invention, in the manufacture of paper carpets or rugs by the usual 15 weaving processes, many difficulties have been encountered, among which may be noted the trouble in causing the weft threads to properly cover the strings or 20 other material of which the warp is composed. Such rugs, before my invention, have also been objectionable for the reason that the rug did not possess the required 25 resiliency or springy effect which is naturally associated with a rug or carpet in the mind of the purchaser or consumer.

The principal object of my invention is to provide a paper yarn of such character 30 that when the yarn is woven into a rug, the warp strands will be properly concealed or covered by the weft threads, while at the same time the rug will possess the desired soft, resilient, or springy characteristics.

In carrying out my invention, I first take 35 a roll of paper as it comes from the mill, slit the same into ribbons of the necessary width, and re-wind said ribbons upon short tubes into the form of disks of paper ribbon. During or prior to the re-winding of 40 the paper ribbon into disk form, the strip is moistened with water, any usual mechanism for effecting such moistening being employed. After the paper ribbon has been re-wound into disk form and while it is still 45 damp, the strip is conducted through a funnel-shaped condensing device of usual construction and is twisted tightly by a well known form of spinning or twisting apparatus, thereby causing it to assume the form 50 of a smooth cord. The damp cord, according to the old practice, was simply wound onto spools, allowed to dry, and then used for weaving the rug or for other purposes. Said dried cord or yarn is practically smooth

as to its exterior surface or finish, is almost 55 devoid of resiliency, and is hard, inflexible, and inelastic.

The process so far described is one which is well known in the art, and, as such, is not claimed as my invention, which resides 60 in the further treating of the paper cord in order to impart to it the desired characteristics.

According to my improved process, the damp cord, which has been wound onto 65 spools after twisting, is preferably permitted to dry out sufficiently for the paper to take a permanent "set", so that during any subsequent treatment the paper will retain the crinkles or striations which have been 70 imparted to the paper by the first twisting. After the yarn has dried out sufficiently on the spools, it is re-wound upon other spools, and, during said re-winding operation, the 75 yarn is passed through a twisting apparatus which is arranged to take out the original twist and impart to it a twist in the reverse direction. This second or reverse twisting of the yarn does not result in the production of yarn which simply possesses a re- 80

verse twist, and is in no other respect different from the original yarn, but, on the contrary, a yarn having characteristics which differ very materially in essential respects from that produced by the first twisting of 85 the yarn while the paper is in a damp condition. My improved yarn made in this way retains the original crinkles, folds, or striations present in the yarn after the first twisting, and, since the re-twisting has been accomplished in the reverse direction, such markings are exposed, made prominent, and project from the exterior surface of the re-twisted yarn, in addition to which, by reason of the markings crossing each other in 90 the interior of the re-twisted cord, the body thereof contains voids or air spaces, thereby causing a substantial increase in the diameter of the yarn and imparting to it flexibility, resiliency, and elasticity to a very 95 marked degree. Such improved yarn possesses all those characteristics which are desirable in a practical and efficient weaving material for the purpose described.

In the drawings—

Figure 1 shows a weft cord composed of two strands of my improved yarn twisted together;

105

Fig. 2 is a plan view of a section of paper ribbon or strip from which the yarn is manufactured;

Fig. 3 is a sectional view of the strip 5 shown in Fig. 2;

Fig. 4 is a plan view of a section of cord formed by the initial condensing and twisting of the strip shown in Fig. 2;

Fig. 5 is a sectional view of the cord 10 shown in Fig. 4;

Fig. 6 is a plan view of a length of my improved yarn completed; and

Fig. 7 is a sectional view of the yarn shown in Fig. 6.

15 In view of the description of the salient features of the process of my invention which has gone before, the invention will be readily understood upon reference to the said drawings. The strip 10 is the ribbon

20 of paper which is wound into disk form in moistened condition before receiving its initial twist. 11 is the same strip after having been condensed and twisted into cord form. A close inspection of Figs. 4 and 5

25 will show that the cord 11 is rod-like, its surface is quite smooth and free from projections or cavities, and, as to its interior, is quite compact and free from voids or air spaces.

30 It will be seen that the completed yarn 12, shown in Figs. 6 and 7, is considerably greater in diameter than the cord 11. Its interior is full of air spaces or voids, caused by the crossing of the original paper markings caused by the first twisting of the 35 paper, and the exterior surface of the yarn shows the markings formed by the first twisting.

In practice, when using the yarn for 40 weaving purposes, I prefer to twist up a pair of the strands 12 into a duplex yarn 13, which constitutes the actual weft material. This enables me to select strands of different colors and produce rugs of various 45 color designs and different patterns. Such a duplex yarn can be very successfully produced from a pair of strands of my im-

proved yarn, for the reason that the spongy or elastic character of the individual strands causes them to bed together, forming a much 50 more uniform and smoother weaving material than if the individual strands were hard or inelastic.

The scope of the invention is not limited to include the precise details herein described, but must be determined by reference to the appended claims. 55

I claim—

1. The improvement in the process of making yarn from paper strip, which consists in condensing the strip, moistening and twisting the same, permitting a substantial percentage of the moisture to evaporate, and subsequently twisting the product in the reverse direction. 60

2. The improvement in the process of making yarn from paper ribbon, which consists in moistening the ribbon, condensing and twisting the same while in moistened condition, permitting the greater part of 70 the contained moisture to evaporate, thereby giving permanence to the markings imparted to the strip by the twisting process, and subsequently twisting the product in the reverse direction, reverse twisting being continued sufficiently to impart to the product 75 a permanent twist opposite to the first twist.

3. The improvement in the process of making yarn from a pair of paper strips, which consists in moistening, individually 80 condensing and twisting the strips while moist, permitting the greater part of the moisture to evaporate, individually twisting the twisted strips in the reverse direction, and pairing the same by twisting them together. 85

4. As an article of manufacture, twisted paper yarn, in the surface of which are formed permanent twist markings formed by pre-twisting the yarn in a direction reverse to the yarn twist, while in slightly moistened condition. 90

BERTRAND S. SUMMERS.
